CLAIM

(22) Filed: **Sep. 11, 2008**

The ornamental design for a sieving hopper for abrasive blasting apparatus, as shown and described.

(30) **Foreign Application Priority Data**

Apr. 9, 2008 (EM) 000913470-0001

DESCRIPTION

(51) **LOC (9) Cl.** **15-09**

The sieving hopper for abrasive blasting apparatus is used in a blasting apparatus having a pressure vessel to contain a particulate blasting medium and a liquid.

(52) **U.S. Cl.** **D15/126**

FIG. 1 is an upper perspective view of the sieving hopper for abrasive blasting apparatus showing my design.

(58) **Field of Classification Search** D15/126,
D15/199; 198/302, 313, 314, 315, 317, 632;
209/241, 247, 420, 421

FIG. 2 is a top plan view thereof;

See application file for complete search history.

FIG. 3 is a bottom view thereof; and,

(56) **References Cited**

FIG. 4 is a side view thereof, a front, back and opposite side view being identical thereto.

U.S. PATENT DOCUMENTS

The broken lines in the drawings depict unclaimed environmental subject matter.
